PROCESSING HYDROCARBON OILS

Maurice H. Arveson, Chicago, Ill., assignor to
Standard Oil Company, Chicago, Ill., a corpo-
ration of Indiana

Application June 25, 1937, Serial No. 150,303

7 Claims. (Cl. 196—50.)

This invention relates to the process of converting heavy hydrocarbon oils, including reduced crude oil and gas oil, to lower boiling oils, particularly gasoline. In the cracking of hydrocarbon oils it has generally been the practice to remove from the crude oil a distillate charging stock or gas oil which was then subjected to pyrolysis at elevated temperatures to convert a portion of it into gasoline, gas and tar. The high boiling point of the tar made it possible to effect a separation between undesirable coke-forming tarry by-products and the unchanged gas oil which was separated as a distillate in an evaporator tower and fractionator and recycled to the zone of pyrolysis. When charging residual stocks to the cracking unit, however, such a sharp separation cannot be made by distillation between the undesirable tar and the unchanged charging stock, and accordingly considerable unchanged cracking stock was lost by being discarded with the undesirable tar.

An object of this invention is to make a clean separation between the unchanged heavy charging stock and the tar produced in the cracking system and to recycle the charging stock until its gasoline-producing potentialities are exhausted. Another object of the invention is to combine a gas oil cracking operation with a residual oil cracking operation, discharging both stocks into the same evaporator tower and extracting the combined tar with a liquefied normally gaseous hydrocarbon to produce an ultimate asphalt and a recovered oil which may be recycled to the cracking zone. Still another object of the invention is to separate from the recovered oil fraction contained in the tar two fractions of different average molecular weight, recycling the heavier fraction to the residual oil cracking zone and the lighter fraction to the gas oil cracking zone. The accompanying drawing, which forms a part of this specification, shows an arrangement of three cracking zones, one for reduced crude, and one each for light gas oil and heavy gas oil, and extraction apparatus for separating asphalt from the recycle oil in the tar and for separating and recycling to different cracking zones, two grades of recycle oil.

Referring to the drawing, reduced crude, which, in this example, may be a Mid-Continent reduced crude, is introduced by line 10 to heater 11 and for this purpose a 40% residual fraction from Mid-Continent crude oil may be employed. In heater 11 the oil may suitably be maintained under a pressure of about 100 to 750 pounds per square inch with an outlet temperature of about

850-930° F. The hot products are conducted by line 12 to evaporator tower 13 where volatile products are removed and unvaporizable constituents are withdrawn as a tar through line 14.

Simultaneously, a heavy gas oil fraction having an A. P. I. gravity of about 25-30 is introduced by line 15 into heater 16 where it is suitably heated to a temperature of about 900-950° F. at any suitable pressure, for example between 200 and 800 pounds per square inch. The hot gas oil vapors are conducted by line 17 to evaporator tower 13 where they mingle with the vapors discharged from heater 11.

Similarly, a light gas oil which may have an A. P. I. gravity of about 30 to 40° is introduced by line 18 into heater 19 where it is subjected to a high cracking temperature in the range of 925 to 1050° F., the pressure being suitably maintained between 200 and 800 pounds per square inch. The light gas oil introduced through line 18 may contain a considerable proportion of heavy naphtha boiling within the gasoline boiling range which it is desired to reform in order to increase its knock rating. The oil discharged from heater 19 is conducted by line 20 and soaking drum 21 to evaporator tower 13 where it is commingled with the oil and vapors from furnaces 11 and 16. Sufficient soaking volume may be supplied in the furnace with the elimination of the drum 21. The hot vapors from the gas oil furnaces assist in distilling the product from heater 11 to produce a clean distillate vapor which is withdrawn from evaporator tower 13 by line 22. Sufficient heat is introduced into evaporator tower 13 by the three hot oil-vapor streams I have just described to effect a clean separation between the volatile fractions and the non-volatile tarry fractions in tower 13. This separation is assisted by reflux cooling coil 23 or other equivalent means of cooling, such as returning a cooled portion of the distillate fraction to the top of the evaporator tower. At an intermediate point of the evaporator tower a heavy gas oil fraction is removed as a side stream by line 24 and conducted to

as a side stream by line 24 and conducted to the inlet of heater 16 for recirculation. This stock will have about the same distillation characteristics as the fresh oil charged by line 15, although the A. P. I. gravity will usually be lower. Vapors from evaporator tower 13 are led by line 22 to bubble tower 25. Gasoline vapors are conducted from the top of said bubble tower to condenser and receiving drum 26 and 27. The condensed liquid fraction separating in bubble tower 25 is withdrawn at the bottom through line 28 by which it is recycled to the inlet of the light

gas oil cracking furnace. If desired, reduced crude oil may be introduced by line 29 into the lower portion of evaporator tower 13, the amount so introduced being regulated to control the temperature and performance of the evaporator tower.

The unvaporized oil or tar withdrawn from evaporator tower 13 by line 14 is conducted through cooler 30 and thence to extractor 31 where it is brought into contact at ordinary temperature, for example 70 to 100° F., with a solvent which is introduced by line 32, the tar suitably passing over baffles for this purpose. The extract solution is withdrawn at the top of the separator through line 33 leading to heater 34 where the temperature is increased to a point in the vicinity of the critical temperature of the solvent. For example, when employing liquid propane as the solvent the temperature of the extract in heater 34 may suitably be about 140 to 220° F. In the case where butane is employed as the solvent the temperature may suitably be raised to about 250 to 315° F. The heated oil is introduced into separator 35 where the increased temperature causes a separation of the extracted oil into two fractions, a light oil and a heavy oil, the light oil together with the major portion of the solvent being withdrawn from the top of separator 35 by line 36 leading to propane evaporator 37 and the heavier oil fraction being withdrawn by line 38 to propane evaporator 39.

The insoluble portion of the tar collecting in the base of extractor 31 is withdrawn by line 40 leading to evaporator 41 where propane is removed and the normally solid asphalt which is substantially free from oil fractions is discharged in the heated condition by line 42. Propane withdrawn from separators 37, 39 and 41 is conducted by lines 43 and 44 to condenser 45, where the propane vapor is reliquefied under pressure and conducted to propane storage drum 46 whence it is withdrawn by line 32 and pump 47 as desired.

The light extract from the base of separator 31, which may have an A. P. I. gravity of about 20-30, is conducted by line 48 to the inlet of the heavy gas oil heater 16 where it is commingled with the heavy gas oil previously described. Thus gas oil which is insufficiently volatile to distil into the upper section of evaporator tower 13 and to recycle to the heavy gas oil heater 16 as a side stream in line 24 will be conducted to the propane extraction system where it may readily be recovered and returned to the gas oil heater 16 as desired. Likewise, heavy constituents of the reduced crude oil which are charged into the system and escape cracking in the initial pass through the heater 11 are recovered in the solvent extraction operation in drum 38, and returned by line 49 to the cracking system for further conversion into gasoline. As a result of this combination of steps I am enabled to obtain a higher yield of gasoline from a given charging stock and at the same time obtain a higher knock rating by virtue of the separation of the stock into a relatively clean light gas oil fraction which may be cracked at a much higher temperature to produce a maximum of anti-detonating constituents. It is preferred to employ a large amount of reflux in evaporator tower 13 for the purpose of "knocking back" tarry constituents which would otherwise be carried through vapor line 22 into bubble tower 25 where contamination of the feed to furnace 19 would result. The heavy gas oil fraction withdrawn by line 24, being of higher molecular weight and more readily cracked, is required to be subjected

to less severe cracking conditions and therefore trouble with coking of furnace 16 is avoided. A still lower temperature is used in furnace 11, the main purpose of which is to viscosity break the reduced crude into products which are subsequently cracked in heaters 16 and 19. By my process I am enabled to employ a high reflux ratio in the upper, baffled section of evaporator 13 without loss of valuable cracking stock in the tar withdrawn through line 14, since this stock is subsequently treated with propane and recovered.

Although I have described my process by specific examples thereof, I intend that my invention be limited only by the following claims.

I claim:

1. The process of converting heavy hydrocarbon oils into motor fuel which comprises viscosity breaking a residual oil in a viscosity breaking zone, cracking a gas oil in a gas oil cracking zone, evaporating the hot products of said viscosity breaking and gas oil cracking operations, separating gasoline from the vaporized fraction of said products, combining and cooling the unevaporated portions of said products, extracting said cooled unevaporated products with a liquefied normally gaseous hydrocarbon solvent at a temperature substantially below the critical temperature of said solvent, separating the undissolved fraction of said products from the extract, heating said extract to a temperature in the vicinity of the critical temperature of the said solvent whereby it is separated into a light recycle oil fraction and a heavy recycle oil fraction, recycling said light recycle oil fraction to the said gas oil cracking zone and recycling the said heavy recycle oil fraction to the viscosity breaking zone.

2. The process of converting heavy hydrocarbon oils into gasoline which comprises subjecting a heavy residual oil to viscosity breaking in a viscosity breaking zone, subjecting a heavy gas oil to cracking in a heavy gas oil cracking zone, subjecting a light gas oil to cracking at a higher temperature in a light gas oil cracking zone, separating the products of said cracking operations into a vaporized and an unvaporized fraction, removing gasoline from said vaporized fraction, cooling said unvaporized fraction and subjecting it to extraction with a liquefied normally gaseous hydrocarbon at a temperature substantially below the critical temperature thereof, separating an insoluble asphaltic fraction from the extract, heating the extract to a temperature in the vicinity of the critical temperature of the said solvent whereby two liquid phases are produced, recovering a relatively light recycle oil from one of said phases and recycling it to said heavy gas oil cracking zone and recovering a relatively heavy recycle fraction from the other of said phases and recycling it to said viscosity breaking zone.

3. The process of claim 2 wherein a distillate fraction boiling above the boiling range of gasoline is separated from said vaporized fraction in a fractionating zone and recycled to one of said gas oil cracking zones.

4. In the process of converting heavy hydrocarbon oils into gasoline of high knock rating wherein a heavy residual incompletely vaporizable oil, a high boiling gas oil and a low boiling gas oil are separately heated to cracking conditions under pressure, whereby the oils are partially converted into gasoline which is separated from the hot products and the unconverted portions of the oils are recycled to the cracking operations, the improvements comprising viscosity breaking the residual oil at a tem-

- perature of about 850 to 925° F. and discharging the hot products into an evaporating zone, heating said heavy gas oil to a temperature of about 900 to 950° F. and conducting the hot products 5 to said evaporating zone, heating the said light gas oil to a temperature of about 925 to 1050° F. and conducting the hot products to said evaporating zone, separating an unvaporized fraction from the vaporized products in said evaporating zone, condensing a portion of said vaporized products as heavy reflux condensate therein and introducing said heavy reflux condensate into said heavy gas oil cracking zone, fractionating said remaining vapors in a fractionating zone to produce 10 a gasoline distillate and a reflux condensate, introducing said reflux condensate into said light gas oil cracking zone, withdrawing and cooling said unvaporized fraction from said evaporating zone and extracting it with a liquefied normally gaseous hydrocarbon solvent selected from the class consisting of propane and butane, removing 15 solvent from the insoluble portion and discarding the high boiling insoluble portion as a high melting asphalt, conducting the extract to a separating zone maintained at a higher temperature in the vicinity of the critical temperature of the said solvent whereby separation into two phases occurs and separating said extract into a light recycle oil phase and a heavy recycle oil phase, 20 removing solvent from said light recycle oil phase and introducing the oil into the said heavy gas oil cracking zone, removing propane from said heavy recycle oil phase and introducing the oil into said viscosity breaking zone.
- 35 5. The process of claim 4 wherein solvent removed from said insoluble fraction and said light and heavy recycle oil phases is condensed and returned to said extraction zone.
6. The process of claim 4 where in a portion 40 of said heavy residual incompletely vaporizable oil is introduced into said evaporating zone below the point of withdrawing said heavy reflux condensate and directly in contact with hot products from said cracking zones whereby said portion is preheated and partially evaporated and said hot cracking products are quenched, thereby preventing undesirable formation of coke in said evaporating zone.
7. In the process of converting heavy hydrocarbon oils to antiknock motor fuels wherein a heavy distillate oil and a light distillate oil are subjected to cracking in separate conversion zones and a residual oil is subjected to viscosity breaking in a third conversion heating zone and the resulting cracked vapors are combined in an evaporating zone, the improvement comprising 10 substantially cooling the vapors released in said evaporating zone and condensing therefrom all coke-forming constituents, subsequently subjecting said vapors free from coke-forming constituents to a fractionating operation and separating them into gasoline and a clean distillate recycle stock, charging said recycle stock to said light distillate conversion zone and subjecting it to a high conversion temperature between 925 and 15 1050° F. whereby a motor fuel of high knock 25 rating is produced, withdrawing from said evaporating zone condensate containing coke forming constituents, cooling said condensate and subjecting it to the selective solvent action of a liquefied normally gaseous hydrocarbon whereby 30 heavy hydrocarbons substantially free from coke-forming constituents are selectively dissolved therein, heating the solution of said heavy hydrocarbons and liquefied gas to a temperature in the vicinity of the critical temperature of said 35 gas, whereby said solution is separated into a heavy fraction and a light fraction, returning said heavy fraction to said residual oil conversion zone and returning said light fraction to said heavy distillate conversion zone.
